FLOOR RACK FOR REFRIGERATOR CARS

William H. Keleher, Chicago, Ill.

Application March 27, 1950, Serial No. 152,197

14 Claims. (Cl. 105—375)

1 This invention relates to insulated refrigerator cars for shipping perishable food products and other products of various kinds and preserving them during shipment from deterioration or decay. More particularly the invention relates to floor racks or false floors for such refrigerator cars which support the lading in the car in spaced relation to the insulated floor of the car so that air, cooled by a refrigerant or heated by a heater, may be circulated through the car and allowed to pass under the lading and up through the false floor and lading to keep the lading in proper condition during shipment.

The racks or false floors heretofore in use have usually consisted of rack sections hinged to the side walls of the car so as to be raised and secured in raised position to allow the car to be cleaned, each rack section being formed of stringers running longitudinally of the car and resting on the floor and provided with an upper load bearing surface comprising spaced slats or plates perforated to allow air circulation upward therethrough and through the lading. These racks are supported in load-bearing position by their stringers which rest directly on the car floor to support the lading at the desired elevation above the car floor.

Up to the advent of the car wheel-driven, floor-located, air circulating fans, now almost universally used in equipping new refrigerator cars, the floor racks generally used consisted of lateral wood slats 3" or 4" in width, and approximately 1" to 1½" thick, running transversely of the car and supported on and fixedly attached to four 2" x 4" wood stringers running longitudinally of the car. The individual sections of floor racks extend from side wall to center line of car, and are of such lengths as to be liftable by one man. In being lifted, they are rotated from the horizontal position to the vertical position and hooked up to the side walls of the car so that refuse may be swept from beneath the racks and out of the doorways of the car. With the advent of the floor rack fan, which required floor racks 7½" in height in order to properly house its impellers, it became necessary to build floor racks of height equal to the fan housing so that the lading can be placed on a plane uninterrupted by differences in levels. This increase in height necessarily adds to the weight of the floor rack because the stringers, whether they be of steel or wood, have to be increased in height and have to be strengthened, which means greater sectional area to prevent buckling under column action.

With labor costs of loading and unloading cars increasing, shippers have resorted to more and more mechanized load handling equipment, in an attempt to keep their costs down. The use of this equipment, together with the use of larger door openings in the past few years on refrigerator cars, has resulted in the use of lift trucks and fork trucks in loading and unloading the cars. These trucks are of considerable weight in themselves and have large load carrying capacities in relation to their size. The use of these trucks has resulted in high wheel-load concentrations, which result in the need for far sturdier floor racks than have been used in the past, and again results in a sharp upward increase in the weight of the floor racks.

For the two above named reasons, namely, the increase in height of the floor racks to accommodate floor type fans and because of the additional strength needed in the floor racks to support concentrations of weight due to the use of lift trucks and fork trucks, floor racks have increased from 50% to 100% in weight over those used a few years ago, and there is every reason to believe that rack weights have not as yet reached their top figure because refrigerator car doors have, up to the present, been limited almost generally to 4' clear widths. As greater door openings are allowed both in width and height, larger trucks will be afforded entry with attendant higher empty and loaded weights. Consequently increased floor rack weights will follow.

35 To keep pace with the increasing weights of floor racks, refrigerator car designers have resorted to more sections and shorter sections in order to not overtax the people who must lift them and attach them to the side walls of the car prior to cleaning beneath the floor racks.

40 A newer and costlier method of aiding the car cleaners in raising the heavy racks has been suggested, and is in the trial stage. This innovation is the use of torsion bar springs at the side wall hinges of the floor racks to counter-balance some of the weight of the racks.

45 During the past years, the use of ice directly in contact with the lading, in fruit and vegetable cars, has become more and more prevalent. The melting of this ice in the body of the car has necessitated refrigerator car design with waterproof floor coverings. This problem has been met by the use of membrane waterproofed floors made up by built-up layers of felt and car flooring cement of asphaltic base. With conventional floor

racks, there is a certain amount of slack or play in the side wall hinges which results in movement of the floor racks on the floor due to vibration and to impacts when the car is struck in the loaded or unloaded state. This movement of the floor rack stringers on the membrane water-proofed floors results in a wearing through of the membrane, with the result that the water-proofing is impaired and water gets beneath the membrane floor, rots the contiguous wood floor, and finds its way into the insulation below the main floor, reducing its insulating value materially, causes deterioration of the insulation, and results in a greater ice or heating fuel consumption depending on the season of the year.

The objects of my invention are to overcome these objections to prior rack structures, and to provide a false floor or rack construction which (1) entirely prevents or reduces wear on the floor due to shifting of the racks and injury to the car floor by rubbing contact of the racks or their stringers therewith, (2) which provides a rack construction of required high-level and embodying rack sections of sufficient strength to support heavy lading but of light weight to enable them to be easily raised and lowered, and (3) to provide a novel construction and arrangement of racks which will permit ready and convenient cleaning of the floor and other parts of the interior of the car.

With these and other objects in view, which will appear in the course of the subjoined description, the invention consists of the novel features of construction, combination and arrangement of parts, hereinafter more fully described, set forth in the appended claims, and shown in the accompanying drawings, in which:

Fig. 1 is a typical sectional plan view of a refrigerator car provided with floor racks embodying the invention.

Fig. 2 is a similar view, on an enlarged scale, showing the racks on one side of the longitudinal center of the car and between the bunker bulkhead at one end of the car and the doorway at said side of the car and including the middle or doorway racks at such side.

Fig. 3 is a plan view of that portion of the car shown in Fig. 2 with the rack sections removed to show the fixed supporting stringers on which the slatted rack sections rest in let down position.

Fig. 4 is a vertical longitudinal section on an enlarged scale taken substantially on line 4—4 of Fig. 2.

Fig. 5 is a view similar to Fig. 4, but taken in a different vertical plane, showing the manner in which a doorway rack section is foldable over upon the adjacent intermediate rack section to which it is hinged to expose the portion of the car floor normally covered by said doorway rack section.

Fig. 5a is a sectional plan view showing the manner in which an intermediate rack section and a doorway rack section hinged to it are foldable to an up-position against a side wall of the car.

Fig. 6 is a vertical transverse section, on an enlarged scale taken on line 6—6 of Fig. 2, through a portion of the car at one side of its center, showing in full and dotted lines one of the intermediate slatted rack sections in its folded and supporting positions, respectively.

Fig. 7 is a similar view, taken on line 7—7 of Fig. 2, looking toward one of the doorway racks, and showing the same in let down position.

Fig. 8 is an enlarged detail section on line 8—8 of Fig. 2.

Figs. 9 and 10 are, respectively, a top plan view and a bottom plan view, on an enlarged scale, of 5 one of the slatted rack sections.

Fig. 11 is a view similar to Fig. 6 showing a modification in which a rack is formed of independent bottom and top hinged units each mounted to swing upwardly and downwardly to inoperative and lading supporting positions.

Fig. 12 is a similar view showing in supporting position another modified form of rack of the type shown in Fig. 11.

Referring now more particularly to Figs. 1 to 15, inclusive, of the drawings, 1 designates an insulated railway refrigerator car of any general conventional or suitable type and which comprises a bottom wall or floor 2, end walls 3 and side walls 4, each provided with a doorway 5, air conditioning (car cooling or heating) bunkers 6 including bulkheads 7 arranged at the ends of the car, and circulating fan housings 8 arranged at the ends of the car adjacent to and spaced inwardly from the bulkheads. The doorways 5, as shown, are arranged midway between the end walls, but may be otherwise arranged, and the bunkers and bulkheads may be of any suitable construction or of the type shown in my prior application, Serial No. 55,599, filed October 20, 1948, in which the bulkhead is provided at its base with a doorway, normally closed by a gate, and which where the gate is opened allows access from the lading space of the car to the space below the bottom of the bunker for ease of cleaning, repairs and other conveniences.

In the form of the invention disclosed in Figs. 1 to 10, inclusive, the portions of the false floor or rack between the doorways and fan housings are composed of fixed or stationary base supporting means or sections and hinged slatted rack sections adapted to rest thereon and to be supported thereby. The base supporting means comprises sets of metal stringers 9 arranged in spaced relation to each other transversely of the car and extending longitudinally at opposite sides of the car between the car center and the housings 8. These stringers, which may be made of steel, aluminum or other suitable metal, have their lower flange portions fixed to the car floor 2 and preferably terminate at their inner ends in line with the sides of the doorways, thus providing clear air circulating and cleaning channels 10 between adjacent stringers and an aisle or clear cleaning space 11 between the doorways, with which space the channels communicate to allow all dirt and refuse to be readily swept out through the doorways in cleaning the car floor.

The stringers 9 are provided to support the intermediate slatted rack sections of the sets of rack sections employed to support the lading, such sets of slatted rack sections comprising intermediate rack sections 12, doorway rack sections 13, and end or bulkhead rack sections 14.

The sets of intermediate rack sections 12, which are designed to cover the space between the doorway and fan housing at each side of the car, may be three in number in each set, as shown, or of any suitable number, to secure desired strength with lightness of weight, and each of these rack sections is formed of longitudinal stringers 15, spaced transverse slats 16 and diagonal braces 17 bolted, riveted, or otherwise rigidly connected together. These

parts may be made of wood, metal (such as aluminum) or a combination of these materials, and the arrangement of the stringers 15 is such that when the sections 12 are disposed in horizontal lading supporting position they will rest on the base stringers 9 which will support the sections 12 above the floor and at the same or substantially the same level as the tops of the fan housings 8. The sections 12 of each set at each side of the car are connected at 10 their outer side edges to the adjacent side wall of the car by double butt hinges 18 and single butt hinges 19, which adapt them to be swung upward against the side of the car and to be secured in upraised position by suitable means, such as a latch hook 20 on each rack section engageable with a keeper 21 on the side wall. In order to secure a firm support for the inner side edges of the let down rack sections 12 at 20 each side of the car the center base stringer 9 is widened by providing it with a seat plate 22, which is welded to its upper flange portion and extends laterally at each side of the stringer to give adequate support to the inner side edges of the sections 12 resting thereon. By making the rack sections 12 independent of the stringers or base supports 9 the weight of each rack section, which may be of any convenient size, may be reduced to a sufficient degree to allow it to be easily swung up and down to inoperative and operative position, at a saving of time and labor on the part of workmen, while when let down the rack sections will be supported at the proper level above the car floor by the 30 stringers which will sustain them firmly against the weight of loading trucks and the weight of lading. When the rack sections 12 are so supported in let down position spaces or channels will be provided below and between the slats of the false floor for ventilating purposes, while when the rack sections are supported in upraised position such spaces or channels will be exposed to allow the car floor to be readily and conveniently swept or otherwise cleaned.

In order to provide a sufficiently strong and light rack flooring across the doorway aisle or space 11, four comparatively small and light weight rack sections 13, arranged as shown, are preferably employed. Each of these rack sections is of a construction similar to that of the rack sections 12, that is, formed of body stringers 15', slats 16' and diagonal reinforcing members 17', but to each of the body stringers of each of the racks 13 is fixedly secured a bottom stringer 23 adapted to rest on the car floor and support the same in let down position. These bottom stringers 23 may be short beams or feet made of light weight metal, such as aluminum, so that each of these racks 13, because of its small size and light weight as compared, for example, with a main rack section, may be easily handled. These rack sections 13 are hinged at their end edges to the adjacent rack sections 12 by double acting hinges 24, adapting each section 13 to be swung over upon the section 12, as shown in Fig. 5, or swung inwardly and upwardly with the section 12 to which it is hinged and folded upon the section 12 to lie in an upraised position against the underside of the section 12, as shown in Fig. 5a. When the sections 13 are swung over on sections 12 or swung upward and secured with the sections 12 in raised position the space 11 will be fully exposed for floor sweeping or other cleaning actions.

The bulkhead rack sections 14 may be generally similar in construction to the doorway rack sections, that is, each may be formed of body stringers 15a, slats 16a and bottom stringers or feet 23a, which parts may be suitably reinforced, but each rack section is preferably made of a length to extend across the car between the car side walls and just sufficient width to cover the space between the bulkhead and adjacent fan housing. Each of these rack sections 14 is connected to the adjacent housing 8 by suitable hinges 25 to adapt it to be supported from the floor 2 by the stringers or feet 23a and to be swung upward to rest upon the fan housing or to be secured to the car side walls. When in let down position the rack sections 14 form loading supports between the fan housings and bulkheads which lie at the same level as the fan housings and other slatted sections of the false floor. When in raised position the sections 14 uncover the car floor spaces between the bulkheads and fan housings to allow access to the drip chambers of the ice bunkers and to said spaces for convenience in conducting clean out, repairs or replacement operations; and as each section 14 is of comparatively small dimensions longitudinally of the car, and as the stringers or feet 23a may be made of light weight metal, said sections 14 may be arranged to extend fully across the car without making them of prohibitive weight, so that they may be easily handled.

From the foregoing description it will be apparent that the invention as thus far described provides a false floor or floor rack having manifold advantages. As the base stringers 9, which support the slatted sections at a proper level above the car floor, are fixed to the car floor against movement and are not raised and lowered with the slatted sections, no shifting of the base supports on or relative to the car floor can occur to cause abrasion or other injury to the car floor, while at the same time this structure permits of the use of slatted or foraminous rack sections which will be firmly supported in lading supporting position and which are light in weight so that they may be quickly raised and lowered with ease and convenience by car cleaners or workmen. Thus the increase in height of the false floor up to the level of the fan housings, so that the lading can be placed on a plane uninterrupted by differences in levels, may be made without adding to the weight of the floor rack sections and without loss of strength of the false floor, as the racks themselves when resting on the bottom stringers will be firmly sustained to prevent breakage or buckling under the weight of loaded trucks or heavy lading. Also as the use of wooden bottom stringers secured to the rack sections is dispensed with, and as the stringers 9, of metal, are fixed to the car floor, the stated disadvantages attendant to the use of wooden stringers subject to injury or decay, or stringers free to shift on the car floor, are avoided and a construction provided which allows ready cleaning of the car and sweeping of all refuse out of the doorways. As, with the exception of that part of the floor area across the car between the doorways, all friction between floor rack stringers and the car floor is eliminated by my construction, the floor insulation material of the flooring at all other portions of the floor area will remain for a long period unimpaired, reducing the amount of ice or heating fuel consumption, depending on the season of the year. With regard to the doorway floor area covered by the rack sections 13, the part of

the membranous water-proof floor covering at this point is necessarily subjected to wearing friction from the rack stringers 23, which are fixed to these rack sections to support them when they are let down and which must be lifted with the rack sections to leave an unobstructed floor space in line with the doorways to permit trucking through the car and also to permit of the ready sweeping out of refuse material swept into the doorway area from the channels formed by the stringers 9 fixed to the car floor. As, however, this doorway area forms only a small portion of the total car floor area, and is the only part of the floor area left vulnerable to wear on the membranous covering from rubbing contact with floor stringers, the amount of repair work and expense necessary to keep the membranous floor covering as a whole in good condition and to avoid damage to the body of the car floor is materially reduced as compared with prior rack installations in which the racks throughout the car are provided with stringers which rest directly on the floor to support the racks in let down position. Furthermore, with my construction all wear due to side wall hinge slack is confined to the wear between the upper load bearing false floor and the tops of the fixed floor stringers, which is not excessive and does not reduce the insulating value of the car.

In Figs. 11 and 12 are shown modified forms of the invention which allow light foraminous floor rack sections to be used with unitary base supporting sections, both mounted to swing, independently of each other, to up and down positions. As shown in Fig. 11 the slatted floor rack section 12^a, which may be constructed and mounted in the same manner as the sections 12, is employed in connection with a base supporting or floor stringer section 9' in which the metal floor stringers 9^a are free from connection with the floor and united by transverse channel beams 26 to form a base supporting unit connected to the car side wall by hinge members 27 to swing downward to rest on the car floor and support the rack section 12^a and to swing upward against the inner side of the section 12^a, parallel with the section 12^a when the latter is swung upward, to expose the car floor to allow it to be swept or otherwise cleaned. The section 9' may be held in its raised position by providing one or more of its transverse channel members with a keeper opening or openings 28 engageable by a fastening hook or hooks 29 on the associated rack section 12^a. This construction allows the sections 12^a, 9' to be made of light weight so as to be easily handled while avoiding the necessity of securing any part of the false flooring to the car floor, and the hinge constructions of these sections may be such as to reduce hinge slack or play and injurious rubbing engagement between the base section and the car floor. Fig. 12 shows a construction of base-supporting unit 9^b similar to the unit 9' of Fig. 11 except that the stringers 9^c are of channel beam form and connected by channel beam cross members 26'. By making the beams of the subsections 9', 9^b of the false flooring of aluminum, base supports of light weight but adequate strength may be provided which are highly durable and may be manufactured and installed with slatted rack sections at a comparatively low cost. While the modified structures shown in Figs. 11 and 12 are not as desirable as that shown in Figs. 1 to 10, inclusive, in that they do not embody stringers fixed to the car floor to support the racks and entirely relieve

the floor from rack friction, they do embody distinct and important advantages over the racks at present in general use in that (1) the top and bottom sections can be lifted separately, so that they may be easily handled, (2) the bottom section when let down forms a firm support for the top or lading supporting section to hold the same at a fixed elevation above and against depression with relation to the floor, and (3) that the wearing friction is divided between the floor and the stringer tops with less damage to the floor than that done by the stringers of the racks now in general use.

From the foregoing description, taken in connection with the drawings, the construction, mode of use and advantages of my improved floor rack will be readily understood and appreciated by those versed in the art without a further and extended description. It is to be understood, of course, that while I have shown the invention in its preferred forms, I do not limit the invention to those shown and described, as various modifications thereof may be employed, within the scope of the appended claims, without departing from the spirit of the invention.

Having thus described my invention, I claim:

1. In a false floor or rack for refrigerator cars, the combination, with a car body having a floor and vertical walls, of supporting means for rigidly supporting a rack from and at a fixed elevation above the floor, and a lading supporting rack formed independently of said supporting means and adapted to be supported thereby against depression in lading supporting position and hinged to the car to swing independently of said supporting means to an upraised position adjacent one of the vertical walls of the car.

2. In a false floor or rack for refrigerator cars, the combination, with a car body having a floor and vertical walls, of supporting stringers of rigid material extending longitudinally of the car in spaced relation to each other transversely of the car and fixed against movement to the car floor, and a lading supporting rack formed independently of the stringers and hinged to the car to swing downwardly to rest on the stringers and to be supported thereby at a fixed elevation above the floor and to be swung free therefrom to a raised position adjacent one of the vertical walls of the car.

3. In a false floor or rack for refrigerator cars, the combination with a car body having a floor and vertical walls, of rigid supporting beams having supporting surfaces for supporting a rack from and at a fixed elevation above the car floor, means connecting said supporting means with the car to hold said supporting means against depression to maintain their supporting surfaces at the fixed elevation above the floor, and a lading supporting rack formed independently of said supporting beams and adapted to rest thereon in lading supporting position and hinged to the car to swing independently of said supporting beams to an upraised position adjacent one of the vertical walls of the car.

4. In a false floor or rack for refrigerator cars, the combination, with a car body having a floor and vertical walls, of supporting stringers of I-beam form extending longitudinally of the car in spaced relation to each other transversely of the car and fixed against movement to the car floor, and a lading supporting rack formed independently of the stringers and hinged to the car to swing downwardly to rest on the upper flanges of the stringers and to be swung free

therefrom to a raised position adjacent one of the vertical walls of the car.

5. In a false floor or rack for refrigerator cars, the combination, with a car body having an insulated floor and insulated side walls, of supporting stringers comprising beams of rigid material extending longitudinally of the car in spaced relation between the side walls and having lower supporting surfaces resting on and fixed to the car floor and upper supporting surfaces located at a level above the car floor, whereby ventilating channels are formed between the beams, and lading supporting racks arranged on opposite sides of the longitudinal center of the car, said racks being free from connection with the strings and hinged to the side walls to swing upwardly to a raised position substantially parallel with said walls and to swing downwardly to rest upon the upper supporting surfaces of the stringers at a fixed level above the floor.

6. In a false floor or rack for refrigerator cars, a refrigerator car having a floor, end walls, side walls, a doorway in each side wall, air conditioning bunkers adjacent the end walls and circulating fan housings arranged adjacent the inner sides of the lower ends of the bunkers and in communication therewith, transversely spaced longitudinally extending ventilating channel forming and rack supporting beams extending longitudinally of the car between the fan housings and sides of the doorway space between the doorways and secured to the car floor, a plurality of foraminous main racks arranged at each side of the longitudinal center of the car on opposite sides of the space between the doorways and the fan housings and hinged to the respective side walls to swing upwardly against the side walls and downwardly to rest on the beams at a fixed elevation above the floor, hinged racks at the ends of the car mounted to swing downwardly or upwardly to cover and uncover the floor space between the bunkers and fan housings, and racks arranged to cover the space between the doorways, said doorway racks being disposed on each side of the center of said space and each doorway rack being hinged to the adjacent main rack at the same side of the doorway space to swing upwardly or downwardly with and into and out of parallel relation with the main rack in the upward and downward movements of the latter.

7. In a false floor or rack for refrigerator cars, a refrigerator car having a floor, end walls, side walls and a doorway in each side wall, stringers extending longitudinally of the car between the end walls and sides of the doorway and in spaced relation to each other transversely of the car and terminating at their inner ends at opposite sides of the floor space between the doorways, said stringers being formed of rigid material and fixed to the car floor against shifting movements relative to the floor, main racks arranged at each side of the doorway at each side of the longitudinal center of the car, said main racks being independent of the stringers and each main rack being hinged to the adjacent side wall to swing upwardly or downwardly with relation to its side wall and the stringers and rest on the latter in lading supporting position, and racks arranged to cover the space transversely between the doorways and between the inner ends of the stringers at opposite sides of the doorway, said racks being movable to positions to cover and uncover the doorway space.

8. In a false floor or rack for refrigerator cars, a refrigerator car having a floor, end walls, side

walls, a doorway in each side wall, air conditioning bunkers adjacent the end walls and circulating fan housings arranged adjacent the bunkers in spaced relation thereto and communicating therewith, stringers extending longitudinally of the car between the fan housings and opposite sides of the doorways and in spaced relation to each other transversely of the car, said stringers being fixed to the car floor and spaced from each other transversely of the car to form intervening air circulating channels, a plurality of foraminous main racks formed independent of the stringers and arranged at each side of the longitudinal center of the car on opposite sides of the space between the doorways and the fan housings, said main racks being hinged to the respective side walls to swing upwardly or downwardly with relation thereto and to the stringers and to rest on the latter in lading supporting position, hinged racks at the ends of the car mounted to swing downwardly or upwardly to cover and uncover the floor spaces between the bunkers and fan housings, and racks arranged to cover the space between the doorways, said doorway racks being disposed on each side of the center of said space and each doorway rack being hinged to the adjacent main rack at the same side of the doorway space to swing upwardly and downwardly with and into and out of parallel relation with the main rack in the upward and downward movements of the latter.

9. A refrigerator car having a floor rack comprising a unitary base section adapted to rest on the car floor and including beams forming supporting stringers and connections rigidly uniting the same, and a foraminous lading supporting section formed independent of and adapted to rest in lading supporting position on the beams of the base section, said sections being free from connection with each other and hinged to the car side wall for upward or downward swinging movements independent of each other and so as to adapt the base section to be swung downward to rest on the car floor and the lading supporting section to be then swung downward to overlie the base section and rest on the supporting stringers thereof.

10. A refrigerator car having a floor rack comprising a unitary base section adapted to rest on the car floor and including channeled beam supporting stringers and connections rigidly uniting the same, and a foraminous lading supporting section formed independent of and adapted to rest in lading supporting position on the stringers of the base section, said sections being free from connection with each other and hinged to the car side wall for upward or downward swinging movements independent of each other and so as to adapt the base section to be swung downward to rest on the car floor and the lading supporting section to be then swung downward to overlie the base section and rest on the supporting stringers thereof.

11. A floor rack of the construction set forth in claim 9 in which the rack sections are hinged to the car side wall at the same level.

12. A floor rack of the construction set forth in claim 9 in which the stringers are connected by channeled cross beams.

13. In a false car floor or rack for a refrigerator car having a floor, end walls, side walls and a doorway in each side wall, said doorways being arranged opposite each other transversely of the car at a point in the length of the car, stringers

of rigid material extending longitudinally of the car between the end walls and doorways and arranged in spaced relation to each other transversely of the car to form channels therebetween and terminating at their inner ends at opposite sides of the floor space extending across the car between the doorways, said stringers being fixed to the car floor against vertical movements and horizontal shifting movements relative to the car floor, and a set of racks arranged at each side of the longitudinal center of the car between the end walls of the car and the doorways, said racks being independent of the stringers and hinged to the side walls to swing upwardly to vertical positions parallel with said walls or to swing downwardly from such positions to horizontal positions to rest on and be supported by the stringers at a fixed elevation above and against depression relative to the floor.

14. In a false floor or rack for a car having side and end walls and a floor, means embodying rigid transversely spaced and longitudinally extending channel forming stringers for supporting

racks from the floor and at an elevation thereabove, and foraminous racks independent of the stringers and hinged to the car side walls to swing upwardly or downwardly toward and from the same and adapted when swung downwardly to overlie the channels and rest upon the stringers.

WILLIAM H. KELEHER.
